G. W. BRAME

FOLDING SWING

Filed Dec. 9, 1922

INVENTOR
George W. Brame.
BY John C. Ferguson
ATTORNEY

UNITED STATES PATENT OFFICE.

GEORGE W. BRAME, OF ST. LOUIS, MISSOURI.

FOLDING SWING.

Application filed December 9, 1922. Serial No. 605,807.

To all whom it may concern:

Be it known that I, GEORGE W. BRAME, a citizen of the United States, residing at St. Louis, in the State of Missouri, have invented certain new and useful Improvements in Folding Swings, of which the following is a specification, containing a full, clear, and exact description, reference being had to the accompanying drawing, forming a part hereof.

My invention consists in the novel construction and combination of parts herein-after particularly described and distinctly claimed.

The object of my invention is to provide an improved folding swing which shall be exceedingly simple in construction, and which may be made in different sizes, as required; is inexpensive to manufacture and easily assembled, as well as very durable, and which invention will, when placed upon a lawn, provide a cool sleeping place for infants and small children in the hot-weather months.

If it is desired to store the swing away in the winter months, the same may be knocked-down and folded into a compact bundle and placed in a closet or other desirable place out of the way until again required for use, or if the invention is of infant size, it may be placed in the nursery and used as a playing place for the infants or small children.

In the drawing,—

Fig. 1 is a side elevation of my improved folding swing.

Fig. 2 is an end elevation of same.

Fig. 3 is an enlarged detail view of one of the top cross-bars, detached.

Fig. 4 is a front elevation of one of the folding side supporting-standards, detached, and in a folded position.

Fig. 5 is a detail plan view of one of the rope-clamps, and

Fig. 6 is a fragmentary detail-view of the lower end of one of the folding side supporting-standards, and the lower cross-bars, showing the manner in which the latter are connected to the said folding side supporting-standards.

In carrying out my invention, I make use of four folding side supporting-standards, designated by the numerals 1, 2, 3, and 4,

and which standards are pivoted together in pairs and form in appearance the letter X, 55 by means of bolts 5, adjacent their upper ends.

Said folding side supporting-standards are sectioned about the center of their length, 60 and are hinged together by means of hinges 6, and to prevent them from folding when in use, I provide four steel plates 7 that are removably fastened thereto by means of bolts 8 and thumb-nuts 9.

Top cross-bars 10 have secured upon their 65 opposite ends by means of bolts 11, suitable L-shaped brackets 12; between the vertical arms of the latter are detachably secured the upper portions of the said folding side supporting-standards 1 and 4 and 2 and 3, by 70 means of bolts 14 and thumb-nuts 15.

Pivottally and detachably mounted upon the said top cross-bars 10, by means of bolts 16, are braces 17 which are used to prevent the said folding side supporting-standards 75 from spreading apart.

The numeral 18 designates braces which have their upper ends pivottally mounted in common screw-eyes 19, and having hooks on their lower ends and adapted to engage 80 the common screw-eyes 20 that are adjacent the upper ends of the said folding side supporting-standards.

Coil-springs 21 have their upper ends pivottally attached to hooks 22 that are screwed 85 or otherwise secured to the underside of the said top cross-bars 10, having ropes or cables 23 slidably mounted in loops on the lower ends thereof.

Said ropes or cables 23 have one of their 90 ends passed downwardly and then upwardly through suitable rope-clamps 24 to form a loop, and are then clamped in the said rope-clamps by means of bolts 25 and thumb-nuts 26. Said rope-clamps 24 are provided upon 95 their inner surfaces with teeth or serrations 27, for more effectually engaging and holding the said ropes or cables from slipping, when the latter are under great or little strain.

The said loops of the said ropes or cables are then detachably connected to suitable hooks 28 secured in any well-known manner to the underside of a crib or seat-bottom 29.

Pivottally mounted upon the opposite ends

of the said crib or seat-bottom 29 are end-gates 30, that are adjustable either up or down, as shown in dotted lines in Fig. 1, and said end-gates 30 are held in the desired adjusted position by any suitable means, such as chains 31, detachably attached to hooks 32 on the said end-gates.

10 Detachably secured to the opposite sides of the said crib or seat-bottom 29 are sides 33 to which the opposite free ends of the said chains 31 are secured.

If it is desired to raise or lower the said crib or seat, the thumb-nuts 26 of additional 15 rope-clamps 34 are loosened and the said ropes or cables 23 are allowed to slide upward or are pulled downward until the desired adjustment is made, when the thumb-nuts 26 are again tightened.

Lower cross-bars 35 have secured to their 20 opposite ends, suitable L-shaped brackets 36, adapted to engage cleats 37 that are secured to and located adjacent the lower ends of the said folding side supporting-standards, as shown in Fig. 6.

25 When it is desired to fold the swing into a small bundle to be placed away, the coil-springs 21 are unhooked from the hooks 22 allowing the crib or seat 29 to be removed from between the side supporting-standards, and the sides 33 are then removed, and the end-gates 30 are folded inwardly upon the said crib or seat-bottom 29.

30 The said top cross-bars 10 and the said bottom cross-bars 35 are then removed, and 35 the said braces 17 are swung back over the said top cross-bars 10, as shown in Fig. 3, and the said folding side supporting-standards are folded in the position shown in Fig. 4, by removing therefrom the said plates 6, 40 after which the parts are gathered together and tied and placed away until again required for use.

45 While I have illustrated certain details of construction which I deemed to be particularly effective, and have illustrated a construction which is very cheap to make and easy to be put up, I do not wish to be limited to these details, as it is obvious that many changes might be made therein without departing from the spirit or scope of 50 my invention.

What I claim and desire to secure by Letters-Patent is:—

1. The combination of a plurality of 55 folding side supporting-standards which are pivoted together in pairs and sectioned about the center of their length; hinges secured to said sections; steel plates that are removably fastened to the said sections, to prevent the latter from folding when in use; top cross-bars; suitable L-shaped brackets secured to the opposite ends of said top cross-bars; braces having one of their ends pivotally and detachably mounted upon the upper portion of the said top cross-bars, 60 and braces having their upper ends pivotally mounted in common screw-eyes, and having provided at their lower ends hooks adapted to engage common screw-eyes located adjacent the upper ends of said folding side supporting-standards. 65

2. The combination of a plurality of 70 folding side supporting-standards which are pivoted together in pairs and sectioned about the center of their length; hinges secured to said sections; steel plates that are removably fastened to the said sections, to prevent the latter from folding when in use; top cross-bars; suitable L-shaped brackets secured to the opposite ends of 75 said top cross-bars; braces having one of their ends pivotally and detachably mounted upon the upper portion of the said top cross-bars; braces having their upper ends pivotally mounted in common screw-eyes, 80 and having provided at their lower ends hooks adapted to engage common screw-eyes located adjacent the upper ends of said folding side supporting-standards; lower cross-bars; suitable L-shaped brackets 85 secured to the opposite ends of said lower crossbars, and cleats secured to the said folding side supporting standards, adjacent the lower ends thereof and adapted to receive the said L-shaped brackets. 90

95 In testimony whereof, I have signed my name to this specification in presence of two subscribing witnesses.

GEORGE W. BRAME.
